UNITED STATES PATENT OFFICE.

CHARLES W. COLLINS, OF SEATTLE, WASHINGTON.

VENTILATING APPLIANCE FOR CLOTHES-DRYING MACHINES.

1,391,939.

Specification of Letters Patent. Patented Sept. 27, 1921.

Application filed November 20, 1919. Serial No. 339,379.

To all whom it may concern:

Be it known that I, CHARLES W. COLLINS, a citizen of the United States, residing at Seattle, in the county of King and State of

5 Washington, have invented certain new and useful Improvements in Ventilating Appliances for Clothes-Drying Machines, of which the following is a specification.

This invention relates to apparatus for 10 the purification of air in clothes-drying machines for separating and removing lint or the like from the air which is utilized as the drying medium.

The invention although especially designed 15 for use in the clothes-drying machine illustrated and described in U. S. Patent No. 1,155,468 issued to me October 5, 1915, may be employed in other applications.

The invention consists in the novel construction 20 and combination of devices which essentially includes a reversible screen which in one position serves to arrest lint or other foreign substances carried by a current of air passing through such screen, and in another or reversed position of the screen the air current serves to remove the collected substances or dirt from the screen.

The invention further consists in the use 25 in connection with a chamber or conduit through which currents of air are caused to travel for the purpose of drying clothes therein of a by-passage through which such air currents escape for the purpose of removing and conveying the dirt from the screen to the external atmosphere.

In the accompanying drawings, Figure 1 is a view partly in side elevation and partly in longitudinal section of a clothes drying machine with the present invention applied 30 thereto.

Fig. 2 is a view partly in front elevation and partly in transverse section of the same. Fig. 3 is a detail sectional view through 35-3 of Fig. 2.

40 The drier shown in said drawings is substantially similar to the one shown in the patent above referred to and illustrates such parts thereof as are deemed necessary for an understanding of my improvements.

45 Referring to the drawings, the numeral 5 designates a substantially U-shaped casing or tank having superposed horizontally arranged conduit members 6 and 7 connected at their rear ends by a curved way 8. At

50 their forward ends, said conduits are each provided with a two-part spring closing

door, of which the upper door 9 opens outwardly and the lower door 10 opens inwardly with regard to the respective conduits.

60

An endless conveyer chain 11 extending about suitable guides, such as 12, passes through both of said conduits, the way 8 and also protrudes from the front of the casing as shown. Said chain is driven as 65 denoted by direction arrows *a* by any suitable means such, for example, as a sprocket wheel 13, Fig. 1, mounted upon a power driven shaft 14.

The numerals 15 represent clothes containing 70 drums having peripheral walls, foraminated or formed of wire screening, and are provided at their ends with axially disposed trunnions rotatably mounted in attachments 11¹ of said conveyer chain.

75

Adjacent to the forward end of the conduit 6 is an opening 16, Fig. 1, communicating with an end of an air heating compartment 17 containing a radiator or system of pipe coils 18 which are connected by a pipe 19 with a source of steam supply, not shown.

Air is admitted at the rear end, desirably of the compartment 17 through an inlet 20, whence it travels among the radiator coils to become heated before entering 85 the forward end of the conduit 6 and through which the air is drawn rearwardly by means of a power driven suction fan or blower 21.

According to the present invention this fan is connected by a pipe 22 with the forward end of conduit 7 and also by means of a by-pass pipe 23 with a chamber 24 which communicates with chambers 25 and 25¹ opening into the top and bottom, respectively, of the conduit 6 in proximity of the 90 rear end of the latter.

95 Provided for the openings 26 between conduit 6 and the chambers 25 and 25¹ are foraminated or screen gates 27, 27¹ hingedly connected to the casing at the rear of the 100 openings 26 by means of fulcrum shafts 28, 28¹. These gates are of sufficient lengths to meet, or nearly so, when swung into the positions in which they are represented by full lines in Fig. 3 whereupon they constitute 105 a transverse partition in the conduit 6.

110 Valves 29 and 30 are respectively provided for the inlet ends of the pipes 22 and 23. These valves are preferably of the balanced or butter-fly type, the same being secured intermediate their widths to crank shafts 29¹ and 30¹. The cranks 29² and 30²

- of the respective shafts are connected by rods 31 and 32 with a crank-arm 33 provided on the fulcrum shaft 28, and the crank-arm 33 of the latter is, in turn, connected by a 5 rod 34 with a crank arm 33¹ provided on the fulcrum shaft 28¹. The aforesaid valves 29 and 30 are operatively connected together by the respective cranks and rods 31 and 32 in a manner so that when one is open the other 10 one is closed. Said valves are, moreover, operatively connected with said fulcrum shafts 28, 28¹ by means of the rod 34 and crank arms 33, 33¹ in such a manner that the screen gates 27, 27¹ will be caused to extend across the duct 6 when the valve 29 is open; and with the valve 30 open when the 15 gates are brought into the openings 26 which communicate through chambers 25, 25¹ with the by-pass pipe 23.
- 20 35 represents a weight attached to a crank arm 33² provided on one of said fulcrum shafts for the purpose of yieldingly holding the gates 27, 27¹ in positions to extend across the conduit 6. 36 represents a crank handle 25 secured to the shaft 29¹ whereby the screen gates and valves may be manually operated and controlled.

The operation of the invention is as follows:

- 30 As the drums 15 are moved in the direction of the feathered arrows shown in Fig. 1, they will successively encounter the screen gates 27, 27¹ to swing the same from the full line positions in which they are shown in Fig. 3 to the positions in which they are indicated by broken lines 27^x in such view. This, it is to be understood, will occur while each drum is passing through the gate-way, so to speak, of the conduit 6.
- 40 After a drum has passed beyond the gates the weight 35 asserts its power to return the gates to their original positions. As hereinbefore mentioned, the valve 30 is closed and valve 29 is open when the gates 45 are in the positions denoted by full lines in Fig. 3 whereby the suction created by the blower 21 will compel all of the air currents from the heating compartment 17 to pass through the screens of the gates when the air 50 is traveling as indicated by arrows W through the conduit 7 to reach the blower connection 22.

When the screen gates are in dotted line 55 27^x positions Fig. 3, or as indicated in Fig. 1, the valve 30 is open and the air currents are diverted through the by-pass pipe 23. Hence it is apparent that the air currents must travel through the screens of the gates in either of the above explained positions 60 of the same. When extending across the conduit 6 the screens of the gates intercept the lint, etc., but when the gates are positioned in the outlets of the conduit into chambers 25, 25¹ the lint, etc., will be on the 65 outer sides of the screens and the air cur-

rents passing outwardly therethrough will be capable of dislodging such substances and conveying them to the blower without passing through the conduit 7.

It may be said that, the clothes when approaching the region of the gates become quite dry and therebeyond the lint becomes exceedingly volatile. Such volatile lint if permitted to travel with the air currents through the conduit 7 becomes saturated with moisture in the latter and if allowed to be deposited upon the drums tend to close the foraminations of the same to prevent the air for drying from passing through the drums with a loss in the efficiency of the machine. The present invention overcomes the above noted objections by withdrawing nearly all of the lint from the machine before the drying air encounters the relatively wet drums.

When it is desirable to continue the bypassing of the drying air for a period longer than would prevail when controlled by the travel of a drum by the gates, the operator may control the gates and valves through the instrumentality of the crank handle 36. This crank handle may also be employed to regulate such apparatus independently of the automatic control accorded by the drums.

What I claim, is—

1. In a clothes-drying machine having a drying chamber with an air inlet at one end thereof, an air outlet at its other end and a second air outlet between such ends, of means to effect the discharge of air through either of said outlets selectively, and a screen arranged to be used interchangeably in both of said outlets.

2. In a clothes-drying machine having a drying chamber with an air inlet at one end thereof, an outlet at its other end and a second air outlet between such ends, and means to effect the flow of air alternately through both of said outlets, a screen gate provided within said chamber, means for regulating said gate to cause the same to be positioned across the chamber and the second named outlet respectively when the air is discharged from said chamber through the first and second named outlets.

3. In a clothes-drying machine having a drying chamber, a suction fan for producing currents of air for drying clothes in said chamber, pipe connections to said fan from one end of the chamber and also from between the ends thereof, valves for regulating the flow of air from the chamber through each of said pipe connections, a screen gate provided in said chamber, and operative connections between the valves and the gate whereby the latter co-operates with the valve controlled currents of air to collect lint on the screen when one of said pipe connections is operative and to deliver the lint thus col-

lected into the other of said pipe connections when the air currents pass through the latter.

4. In a clothes-drying machine having a drying chamber provided with an outlet at one end and a second outlet intermediate its ends, an air fan connected with both of said outlets, valves for the respective outlets, a screen gate operatively connected to both of said valves, means to yieldingly retain said gate in position to screen the air passing through the aforesaid end outlet, a clothes containing drum, and means to effect the travel of said drum through said chamber whereby said drum is instrumental in moving the gate and valves into positions whereby the air is caused to be temporarily discharged from the chamber through the gate and the second named outlet.

5. In a ventilator for clothes drying-ma-
20 chines, the combination with a drying chamber having an air inlet at one end, an air outlet at the other end and a second outlet intermediate the length of said chamber, a suction fan, pipe connections between each of

said outlets and the fan, and valves for the 25 respective pipe connections, of a screen gate provided interiorly of the drying chamber, and means for operating said gate to position the same alternately across the second named outlet and across the chamber between the 30 two outlets, said means being connected with said valves whereby the said fan is rendered operative to effect the passage of air through said gate in both of the aforesaid positions thereof.

6. In a clothes-drying machine, a suction fan for supplying clothes drying air to the machine, a screen gate provided in the ma-
35 chine, and means to regulate the position of the gate whereby the air is caused to pass 40 alternately through the gate from opposite sides thereof.

Signed at Seattle, Washington, this 10th day of October, 1919.

CHARLES W. COLLINS.
